UNITED STATES PATENT OFFICE.

GEORGE O. TERRY, OF MINNEAPOLIS, MINNESOTA, ASSIGNOR TO ECONOMY SHOE MACHINE CO., OF MINNEAPOLIS, MINNESOTA, A CORPORATION OF MINNESOTA.

SHOEMAKER'S JACK.

1,414,055.

Specification of Letters Patent. Patented Apr. 25, 1922.

Application filed April 24, 1920. Serial No. 376,281.

To all whom it may concern:

Be it known that I, GEORGE O. TERRY, citizen of the United States, residing at Minneapolis, in the county of Hennepin and State of Minnesota, have invented certain new and useful Improvements in Shoemakers' Jacks; and I do hereby declare the following to be a full, clear, and exact description of the invention, such as will enable others skilled in the art to which it appertains to make and use the same.

My present invention has for its object to provide a highly efficient shoemaker's jack for use in holding shoes while nailing soles, heels, and trimming.

To the above end, the invention consists of the novel devices and combinations of devices hereinafter described and defined in the claims.

20 In the accompanying drawings, which illustrate the invention, like characters indicate like parts throughout the several views.

Referring to the drawings:

Fig. 1 is a view in side elevation with some parts broken away and sectioned, and also illustrating, by means of broken lines, a shoe held on the last of the jack;

Fig. 2 is a horizontal section taken on the line 2—2 of Fig. 1;

30 Fig. 3 is a detail view in section taken on the line 3—3 of Fig. 1;

Fig. 4 is a detail view in section taken on the line 4—4 of Fig. 1;

35 Fig. 5 is a view corresponding to Fig. 1, with the exception that the jack is adjusted in a different position; and

Fig. 6 is a view partly in elevation and partly in vertical section taken on the line 6—6 of Fig. 1.

40 The improved jack includes a tubular standard made up of a lower section 7 and an upper section 8, the former of which is rigidly secured to a floor or other support by lag screws 9. The abutting ends of the standard sections 7 and 8 are contracted to afford bearings 10 and 11, respectively, and which bearings have at their opposite extremities annular shoulders 12 and 13, respectively.

50 The standard sections 7 and 8 are connected by a laterally offset hinge 14 arranged to open on the horizontal pivot of a friction joint. This hinge 14 is connected to the lower standard section 7 for horizontal swinging movement and said upper standard

section 8 is mounted therein with freedom to be turned on its longitudinal axis. Said hinge 14 comprises upper and lower overlapped members 15 and 16, respectively, and a horizontal nut-equipped pivot bolt 17, 60 which extends through aligned bores in said members. A coil spring 18, encircling the bolt 17, is compressed between the lower hinge member 16 and a washer 19 on said bolt at the nut-equipped end thereof and frictionally draws the members of the hinge 14 together. Formed with the hinge members 15 and 16 are transversely divided hubs 20 and 21, respectively, and which hubs are turnably mounted on the bearings 11 and 10, 65 respectively. These hubs 20 and 21 have offset ears 22, which extend substantially parallel to the members 15 and 16 of the hinge 14 and are laterally spaced therefrom. Thumb-nut-equipped draw-bolts 23 extend 70 through aligned bores in the ears 22 and hinge members 15 and 16 and are provided to frictionally clamp the hubs 20 and 21 on the bearings 11 and 10, respectively, and thereby lock the hinge 14 against turning 75 movement on the lower standard section 7 and the upper standard section 8 against turning movement on the hinge 14.

A last 24 is removably and reversibly mounted on the upper end of the upper 80 standard section 8 by forming on said section a tenon 25 arranged to fit within a mortise 26 in said last. For holding a shoe Z firmly on the last 24, I provide a buckle-equipped strap 27 adapted to be extended 85 over the shoe close to the heel thereof. The sections of the strap 27 are secured by rivets to the intermediate portions of a pair of converging prongs on a bifurcated lever 28, which loosely embrace the upper standard 90 section 8. The prongs of the lever 28 are pivoted at 29 to a radially projecting lug 30 integrally formed with said standard section 8, and which pivot 29 permits a limited lateral movement of said lever.

To hold the lever 28 with the strap 27 tightly drawn downward over the shoe Z, there is secured to one of the prongs of said lever a lock dog 31 arranged for co-operation with a plurality of ratchet teeth 105 32 secured to a vertical web 33 integrally formed with the standard section 8 diametrically opposite the lug 30. The ratchet teeth 32 are arranged to permit the dog 31 to slide thereover under a downward move- 110

ment of the lever 28 to tighten the strap 27 and lock the same against upward movement to release said strap.

A spring-pressed plunger 34 is mounted 5 in one of the prongs of the lever 28 and yieldingly engages the opposite side of the web 33 from the ratchet teeth 32 to yieldingly hold the lever 28 in a position with the lock dog 31 in engagement with the 10 ratchet teeth 32. If the movement of the lever 28 in drawing the strap 27 over the shoe Z is too great for the number of ratchet teeth 32, said strap may be shortened by means of the buckle interposed therein. The 15 yielding engagement of the lock dog 31 with the ratchet teeth 32 will automatically hold the lever 28 at the limit of its downward movement, and to release said lever, it is only necessary to move the same laterally 20 against the action of the spring-pressed plunger 34 to disengage the lock dog 31 from the ratchet teeth 32 and permit said lever to be raised.

By bifurcating the lever 28 so as to embrace 25 the upper standard section 8 and attaching the ends of the strap 27 to the prongs of said lever, it is possible to secure a direct downward pull on said strap over the shoe, which is desirable in securing said 30 shoe firmly on the last.

By loosening the lower draw-bolt 23, the hinge 14 may be turned on the bearing 10 and set in any desired position, or by loosening 35 the upper draw-bolt 23, the upper standard section 8 may be turned on its longitudinal axis to position the last 24 to suit the operator. The spring 18, acting on the hinge bolt 17 and the lower hinge member 16, frictionally clamps the upper hinge 40 member 15 on said lower hinge member 16 with a force sufficient to yieldingly hold the upper standard section in an upright position or in various different oblique positions in respect to the vertical. By the

use of the friction joint in the hinge 14, 45 an operator may very quickly and easily set the upper standard section 8 in any desired position and then turn said upper standard section on its longitudinal axis while working on a shoe, for instance, in 50 trimming the rough outline of a sole to a welt. By adjusting a nut on the hinge bolt 17, the tension of the spring 18 may be varied, at will.

What I claim is:

1. A shoemaker's jack having in combination a lower standard comprising a bottom attaching flange and a post upstanding therefrom having a shouldered journal at its top, an upper standard adapted to support a last and having a shouldered journal at its lower end, and a connection for said standards comprising superimposed split clamping sleeves, the upper one receiving the journal of the upper standard and supporting said standard and the lower one fitting over the journal of the lower standard and supported thereby, said sleeves having laterally extending arms connected by a hinge friction joint, the diameters of 60 said sleeves and the adjacent ends of the standards being substantially the same.

2. In a shoemaker's jack, the combination with a standard having a last, of a bifurcated lever embracing the standard and pivoted thereto with freedom for a limited lateral movement, a strap extending over the last and having its ends secured to the prongs of the lever, a lock pawl on the lever and co-operating ratchet teeth on the standard for holding the lever in different adjustments, and means under strain to move the lever laterally and yieldingly hold the lock pawl in engagement with the ratchet teeth.

In testimony whereof I affix my signature.

GEORGE ORVILL TERRY.
